US0D1109801S

(12) **United States Design Patent** (10) **Patent No.:** **US D1,109,801 S**
Hoddinott (45) **Date of Patent:** **** Jan. 20, 2026**

(54) **POSTER FOR GUIDE TO DOUBLE SEAM DEFECTS**

(71) Applicant: **Crown Packaging Technology, Inc.**,
 Tinley Park, IL (US)

(72) Inventor: **Katie Hoddinott**, Wantage (GB)

(73) Assignee: **Crown Packaging Technology, Inc.**,
 Tinley Park, IL (US)

(**) Term: **15 Years**

(21) Appl. No.: **29/966,972**

(22) Filed: **Oct. 7, 2024**

(30) **Foreign Application Priority Data**

Apr. 9, 2024 (GB) 6358219

(51) **LOC (15) Cl.** **19-07**

(52) **U.S. Cl.** ..... **USPC** **D19/59**

(58) **Field of Classification Search**

USPC ... D19/59, 100, 1, 2, 3, 5, 6, 20, 24, 25, 37,
 D19/75, 86, 90; D14/485, 492, 494;
 D20/20-32

CPC G06F 16/54; B65B 61/18

(57) **CLAIM**

The ornamental design for a poster for guide to double seam defects, as shown and described.

DESCRIPTION

The patent or application file contains at least one drawing executed in color. Copies of this patent or patent application publication with color drawing(s) will be provided by the Office upon request and payment of the necessary fee. The sole FIGURE is a front elevational view of the poster for guide to double seam defects on flat material.
